UNITED STATES PATENT OFFICE.

HERMAN IHLENBURG, OF PHILADELPHIA, PENNSYLVANIA, ASSIGNOR TO THE MACKELLAR, SMITHS, & JORDAN CO., OF SAME PLACE.

DESIGN FOR A FONT OF TYPE.

SPECIFICATION forming part of Design No. 16,343, dated October 20, 1885.

Application filed August 11, 1885. Serial No. 174,161. Term of patent 14 years.

To all whom it may concern:

Be it known that I, HERMAN IHLENBURG, (assignor to the MacKellar, Smiths, & Jordan Co.,) of the city and county of Philadelphia, Pennsylvania, have invented and produced a new Design for a Font of Printing-Type, of which the following is a specification.

The nature of my design is clearly shown in the accompanying typographic impressions, to which reference is made; and it consists of a letter resembling the class known as "Medieval."

The letter is unshaded, and the up and down portions of the letters, as in the A, B, D, F, H, N, P, and T, are wider at the bottom than at the top. The A, F, M, and T are ornamented at the top by the heavy curved flourishes, as shown. The B, C, D, E, N, S, V, W, X, Y, and Z have the heavy curved termination, as shown. In the B, D, and N it is found at the base upon the right hand; in the others upon the right and left, except in the V and W, in which it is shown upon the upper right hand. The cross-lines of the A consist of two short parallel lines. The H and O are ornamented by a single cross-line. The upper right-hand termination of the K curves to the left. The cross-line of the E gradually widens upon the right to form a triangular termination. The cross-line of the F is curved, as shown. The termination of the J upon the left is widened and curved to the right. The cross-line of the G terminates upon the left in the heavy dot, as shown. The upper portion of the L is extended to the right and terminates in the heavy dot. Its lower termination is extended upon the right and terminates in the heavy curve, as shown. The tail of the Q consists of the curved line, the terminations of which are gradually widened.

The character of the design is preserved in the lower-case, notably in the e, e, f, g, h, k, n, o, t, u, v, w, x, y, and z, and in the numerals.

In connection with the font are shown four typographic adjuncts. The first consists of a heavy dot, outside of which are placed four heavy spear-head-like ornaments, followed by the central lines terminating in the dot-like ornaments. The space between the four spear-head-like ornaments forms a cruciform figure.

The second consists of a heavy line with curved terminations curving to the right, crossing a heavy heart-shaped figure. From this heavy heart-shaped figure upon the left proceeds a line terminating in a spear-head-like ornament from which lines above and below proceed the short light inclined lines, followed by the heavy spear-head-like ornaments. The third consists of a circular figure composed of a heavy central dot, around which are placed a series of heavy spear-head-like ornaments, between which an open space is left. The fourth consists of a heavy central dot, from which proceed, above, below, upon the right, and upon the left, four curved lines, widening as they terminate and crossing a light circular figure or ring, of which the dot forms the center.

Having now described my invention, I claim as new—

left proceeds a line terminating in a spear-head-like ornament, from which line above and below proceed the short inclined lines, followed by the heavy spear-head-like ornaments, the 5 third typographic adjunct consisting of a circular figure composed of a heavy central dot, around which are placed a series of spear-head-like ornaments, between which an open space is left, the fourth typographic adjunct consisting of a heavy central dot, from which proceed, above, below, upon the right, and upon the left, four curved lines, widening as they terminate, and crossing a light circular figure or ring, of which the dot forms the center, and the character of the design preserved in the 15 lower-case and numerals.
